United States Patent Office

Des. 185,041
Patented Apr. 28, 1959

185,041

CHILDREN'S PLAY HOUSE

Gladys L. Sanderson and Herbert C. Sanderson,
Sacramento, Calif.

Application August 13, 1957, Serial No. 47,351

Term of patent 3½ years

(Cl. D34—15)

Fig. 1.

Fig. 2.

The opposite side, not shown, has substantially the same appearance as the side shown in the drawing.

We claim:

The ornamental design for a children's play house, as shown and described.
